UNITED STATES PATENT OFFICE.

HERMAN RIGERT, OF WATERBURY, CONNECTICUT.

SNAP-FASTENER.

1,275,473.

Specification of Letters Patent. Patented Aug. 13, 1918.

Application filed August 12, 1914, Serial No. 856,374. Renewed February 18, 1918. Serial No. 217,992.

To all whom it may concern:

Be it known that I, HERMAN RIGERT, a citizen of Switzerland, and a resident of Waterbury, in the county of New Haven 5 and State of Connecticut, have invented certain new and useful Improvements in Snap-Fasteners, which improvements are fully set forth in the following specification.

This invention relates to improvements in 10 two-part devices of that class quite extensively availed of for garment fastening purposes, such devices being commonly known as snap-fasteners.

The object of this invention is to provide 15 a snap-fastener of the character above indicated, which shall be simple and inexpensive as regards its construction; durable, efficient and reliable in practical service, and which shall possess certain well-defined advantages over prior analogous constructions.

The invention consists in the combinations, details and parts whereby, together with the novel disposition and relative arrangement of said parts, the attainment of 25 the foregoing object is rendered practicable, all of which will be hereinafter more specifically referred to and set forth in the claims hereto appended.

The invention is clearly illustrated in the 30 accompanying drawing, wherein:

Figure 1 is a plan view of a snap-fastener embodying my said improvements, the main members thereof appearing in the positions they respectively assume when 35 brought into locking engagement, each with the other.

Fig. 2 is a view similar to Fig. 1, the stud-affording member of the device appearing as having been rocked upwardly out of its 40 frictional engagement with the opposite, elastic member thereof, but not wholly detached therefrom.

Fig. 3 is an edge elevation of the device, the stud-affording member thereof appearing as having been rocked upwardly approximately as defined in the description of 45 Fig. 2.

Fig. 4 is a central, longitudinal section of the device, as along the dotted line $x-x$ of 50 Fig. 1.

Fig. 5 is a view showing in plan the elastic main member of the device attached, as by stitching, to a fragment of a wrist-band or similar fabric.

Fig. 6 is a view similar to Fig. 5, showing the stud-affording member of the device at-

tached, as by stitching, to a fragment of a wrist-band or like fabric.

Having reference to the accompanying drawing, wherein similar reference-characters denote like parts throughout the respective views, I, in carrying out my present invention, make use of a stud-affording main member, which may be formed from any suitable material, preference being given to metal in thin sheet-form, and which comprises a duly elongated body 2, provided at one end with a stud 2', and at its opposite end with a tang 2''. The stud 2' and tang 2'' are offset in one and the same general direction from the body 2, the free end-portion of said tang being turned away from said stud and disposed to lie in parallelism, approximately, with the plane of said body.

The stud-affording member aforesaid is 75 provided with eyes, 3, 3', for facilitating the mounting thereof, as by stitching, on, say, a wrist-band, as 3''.

Both the stud 2' and the tang 2'' may be advantageously formed integral with the body 2, and each given its required specific form, as clearly indicated in the drawing.

I further make use of an additional main member, duly elongated and in itself elastic, the same being formed from any suitable material, as wire of an appropriate gage and possessing measurable resiliency, said main member being socketless, affording a primal stress-bar 4, at one end thereof, and having formed integral therewith, at its opposite end, an elastic stud-grasping element.

More specifically in this connection, said additional member comprises opposite side-bars, 4', 4'', integrally connected at the neighboring ends thereof by the primal stress-bar 4, either or both of said side-bars possessing a measurable degree of elasticity, and the member as a whole approximating in general form the character **U**.

While I have shown the last-named main member of my improved snap-fastener as being provided with eyes 5, 5', for facilitating the mounting thereof, as by stitching, on, say, a wrist-band, as 5'', it is obvious that the mounting of the member now under consideration may be otherwise accomplished.

In a general sense the free end-portion, as 6 or 6', of either of the side-bars aforesaid, may constitute and serve as, the 110 stud-grasping element hereinbefore mentioned, this being obviously so where the

eyes 5, 5', are omitted, or given formation in a manner other than as herein defined, the end-portions of said side-bars, under such conditions, being so relatively arranged, normally, as to duly contract the space therebetween.

In this instance, however, said stud-grasping element performs its function, as will appear more fully hereinafter, indirectly 10 through the medium of the material availed of in giving formation to the eye, as 5 or 5', adjacent thereto and formed thereon, the end-portions of the side-bars aforesaid being, under such conditions, so relatively 15 arranged, normally, as to duly contract the space intervening between the respective eyes 5, 5', as clearly shown in the drawing.

As to the operation of my improved fastener, the main members thereof having 20 been duly mounted on the opposite meeting margins, respectively, of a garment, wristband, or the like, as in common practice, the user brings such meeting margins into such registry as to permit, primarily, the engagement, after the general manner of a hook, of 25 the tang 2" with the primal stress-bar 4, the stud-affording member aforesaid being now positioned relatively to the additional or elastic member aforesaid, as though 30 having been rocked out of registry therewith, as on the primal stress-bar aforesaid and through the medium of the tang 2", (see Fig. 2); whereupon the user rocks the stud-affording member of the device over and 35 upon the elastic or additional member thereof, and sufficiently so to cause frictional engagement of the stud 2' by the elastic stud-grasping element aforesaid, the main parts of the device being then securely locked together.

During the operation aforesaid of rocking the stud-affording member of the device over and upon its coöperating main member, a substantial leverage is exerted, through 45 the medium of the tang 2" and the stress-bar 4, whereby the meeting margins of the garment, are drawn more fully into registry, each with the other, this feature of my improved fastener being highly advantageous.

Again, when the main members of my improved fastener shall have been locked together as hereinbefore explained, all stress, such as may ordinarily be brought to bear on the device as a whole, in practice, is mainly 55 resisted, not by the frictional holding force exerted on the stud 2', but by the tang 2" in conjunction with the stress-bar 4, this constituting an additional important feature of my improved fastener, and one rendered all the 60 more feasible by the fact that the frictional holding force, exerted on the stud 2', while being sufficient to prevent any rocking action on the part of the stud-affording member aforesaid relatively to its coöperating 65 main member, still permits a measurable to

and fro movement on the part of said stud-affording member in parallelism with its coöperating main member.

It will be apparent that when the respective main members aforesaid shall have 70 been locked together, as hereinbefore explained, the device as a whole will present a generally flat form; of minimum height or elevation.

It will be seen that my improved snap- 75 fastener is well adapted for the purpose for which it is intended, and further that the same may be modified to a considerable extent, particularly as regards the specific character of the elastic stud-grasping ele- 80 ment made use of, and various minor details of the general construction, without departing from the scope of the claims hereto ap- 85 pended.

I claim:

1. A snap fastener comprising two co- 90 operative separable members attachable to opposite meeting margins of a garment or the like, one of said members being formed from wire and having opposite, elastic side- 95 arms connected integrally by a stress-bar, and normally contracting the space between and at the free end-portions thereof, and the other of said members having a tongue and a stud at opposite marginal points at one and the same face thereof, said tongue turned rearwardly away from said stud and adapted to engage and rock on said stress-bar, and said stud being adapted to enter, with a snap action, and occupy at the point of its 100 greatest contraction, the space aforesaid between the free end-portions of said side- 105 arms, when said separable members are being connected.

2. A snap fastener comprising two co- 110 operative separable members attachable to opposite meeting margins of a garment or the like, one of said members being formed from wire and having opposite, elastic side- 115 arms connected integrally by a stress-bar, the free end-portions of said side-arms being turned, each in the direction of the opposite side-arm, and merged accordingly into opposite attaching-eyes, and the other of said members having a tongue and a stud at oppo- 120 site marginal points at one and the same face thereof, said tongue turned rearwardly away from said stud and adapted to engage and rock on said stress-bar, and the stud aforesaid being adapted to enter, with a snap action, and occupy the space between the attaching-eyes aforesaid, when said separable members are being connected.

3. A snap fastener comprising two co- 125 operative separable members attachable to opposite meeting margins of a garment or the like, one of said members having oppo- 130 site, elastic side-arms connected integrally by a stress-bar, said side-arms merged at their free ends into opposite attaching-eyes,

and the other of said members being constructed from material in sheet form, and supporting thereon, at opposite marginal points of one and the same face thereof, a 5 tongue and a stud, said tongue turned rearwardly away from said stud and adapted to engage and rock on said stress-bar with a leverage effect, and said stud being adapted

to enter, with a snap action, and occupy the space between the attaching-eyes afore- 10 named, when said separable members are being connected.

HERMAN RIGERT.
